UNITED STATES PATENT OFFICE

100,262

DESIGN FOR AN AIR-CONDITIONING CONTROL DEVICE OR SIMILAR ARTICLE

Lucien L. Friez, Baltimore, Md., assignor to Bendix Aviation Corporation, South Bend, Ind., a corporation of Delaware

Application November 18, 1935, Serial No. 59,642

Term of patent 14 years

To all whom it may concern:

Be it known that I, Lucien L. Friez, a citizen of the United States, residing at Baltimore, State of Maryland, have invented a new, original, and ornamental Design for Air Conditioning Control Device or Similar Article, of which the following is a specification, reference being had to the accompanying drawing, forming part thereof.

In the drawing:

Fig. 1 is a front elevation of an air-conditioning control device showing the design of the present invention;

Fig. 2 is a side elevation thereof; and

Fig. 3 is a top view thereof.

The dominant features of the design are shown in full lines of the drawing, while the dotted lines indicate features which are not important to the invention disclosed.

I claim:

The ornamental design for an air-conditioning control device or similar article, as shown and described.

In testimony whereof, I have hereunto signed my name.

LUCIEN L. FRIEZ.
